LOUIS NADEL, OF NEW YORK, N. Y., ASSIGNOR TO PIERCE STEEL PILE CORPORATION, OF NEW YORK, N. Y., A CORPORATION OF NEW YORK

METHOD AND APPARATUS FOR FORMING PILES

Application filed December 16, 1930. Serial No. 502,688.

This invention relates to that branch of the art of made-in-place concrete piles in which an inexpensive thin sheet-metal shell is sunk into the ground and serves as a form for the casting of the concrete, the shell remaining in place and constituting the skin of the pile in contact with the surrounding soil, but forming no part of the structural strength of the pile.

10 The actual practice in operations of this character is to employ a tapered shell, resulting in a tapered pile, and to drive the shell with a collapsible core, this core being expanded into close contact with the tapered shell for the driving operation, so that the driving power of blows delivered on the top of the core is distributed over the length of the shell. The core is in effect a preparatory pile carrying the shell with it as a skin. The 15 shell is customarily corrugated or reinforced in some similar manner, and the core is formed to engage the corrugations and thereby push the shell into the ground. While there may have been other proposals, this has been the 20 practice as far as I am aware.

Objects of this invention are to utilize a thin sheet-metal shell or form, to do away with expensive expandible cores, which are subject to derangement under hammering 25 with the result that there is often much difficulty in removing them, and to produce piles which, being of uniform cross-section throughout, or substantially so, do not diminish in bearing value from the top to the bottom.

30 I employ a cylindrical sheet metal shell, preferably though not necessarily corrugated for reinforcement, and sink this shell by transmitting driving power through a mandrel directly to the point of the shell, so that the shell is sunk by a pulling action applied at its lower end.

Under this invention a solid mandrel, such as one consisting of one or more sections of 35 heavy pipe, may be employed, such a mandrel being strong and inexpensive and being easy to remove before introducing the concrete, after the shell has been sunk to its final position.

40 The shell is provided with a boot which

closes its lower end, and the mandrel may be provided with a driving end adapted to the boot.

The point of the shell may be formed by a sheet metal boot, the top of which receives the lower end of the shell and is welded to the outside of the shell wall. In this way the boot is not only strongly united to the shell, so that the latter will be pulled down into the ground without possibility of separation, 55 but in addition the bottom of the pile shell is sealed, thus making it water-tight. The lower end of the shell is provided with a reinforcement, which affords internal support for the rim of the boot, and by turning said rim inward over this reinforcement a specially 60 strong construction is secured.

In an alternative construction, the lower end of the shell is simply tapered so as to lie and be clamped between the similarly tapered boot and mandrel point. This combination also insures that the shell will be drawn downward without escaping from the driving point and the walls of the shell and boot are held together so firmly that there is little opportunity for the entrance of water. 75

Other modifications will suggest themselves to those skilled in the art, and it will be understood that numerous changes may be made in the details and by way of substitution, addition or omission, without departing 80 from the scope of the invention.

In the accompanying drawings forming part hereof:

Fig. 1 is a vertical sectional view, with intermediate portions broken away, showing the shell partly sunk with the aid of the solid mandrel;

Fig. 2 is a vertical sectional view, with intermediate portions broken away, showing the shell in final position in the ground and filled with the concrete forming the pile;

Fig. 3 is a vertical section on a larger scale of the lower end of the shell and the boot forming the point of the shell, this view being further illustrative of the form of the invention shown in Figs. 1 and 2; and

Fig. 4 is a vertical section of the lower portions of the shell and mandrel, and of the boot, in another form of the invention. 100

The pile shell is marked 2. It is made of commercial cylindrical sheet steel or sheet iron pipe, produced in any of the ways in which such pipe is manufactured, and is preferably corrugated for stiffness, the corrugations preferably running spirally. Metal of about sixteen to twenty gauge is satisfactory for my purpose.

A tapered sheet steel boot 3 of heavier gauge forms the point of the shell. Such a point can be cheaply formed by a pressing operation and has adequate strength for the severe duty required of it.

The lower edge of the shell is rolled to form a reinforcing bead 4, which is preferably strengthened by an internal wire 5. The rim or top of the boot extends upward outside of the lower end of the shell,lapping the same for a distance of some inches, and above the reinforcement 4, it is turned inward to a smaller diameter than the reinforcement and is permanently united to the outside of the shell by a continuous weld 6. By turning the edge of the boot into one of the corrugations of the shell and making the weld beneath the overhang of the corrugation an exceptionally strong and water-tight joint can be produced.

The mandrel 7 is obtained at minimum expense by utilizing a length of ordinary heavy-walled pipe. It is termed a solid mandrel in contradistinction to the collapsible cores which have been employed. A cast point 8, conforming to the internal shape of the boot, is fixed to the lower end of the mandrel, by shrinking it on, or otherwise.

The mandrel may be materially smaller than the inside diameter of the shell, so that there is a free clearance between the outside of the mandrel and the inside of the shell throughout the full length of these members, in which case the only fitting of the parts is at the point, these being of such nature that the boot is fully supported under impacts and the shell is kept vertical.

All of the driving force is transmitted to the point, and the shell is drawn down into the ground, as previously stated. When the proper resistance has been encountered, the mandrel is withdrawn freely, without possibility of catching or jamming, and the concrete 9 to form the actual pile is then introduced.

If a single section of shell does not prove long enough, or if short sections are used, a second section 2^a is added. For this purpose a corrugated band 10 is used, the band being preferably bound in place by wires 11. Instead of a band, a sleeve in the nature of a screw coupling might be used. Still other sections can be added in the same manner. The sections of the shell may be as numerous as desired.

The mandrel is also extended, as necessary, by adding one or more additional sections 7^a, an internal sleeve 12 having a flange 13 inter-

posed between the ends of the sections of heavy-walled pipe being employed to hold these sections in relation to each other. These couplings need not fasten the sections together, a slip engagement being sufficient. When the driving has been completed, the upper section of the mandrel is lifted out, and a hook or grapple is then lowered to catch a bar 14 fixed in the lower section.

In the modification shown in Fig. 4, the lower end portion of the shell 20 is left plain, that is to say, without corrugations, and it is drawn inward on a taper 21 corresponding to the taper of the mandrel point 8 and the taper of the boot 30. The tapered portion of the shell extends for a considerable distance between said point and boot, and while the parts are not united the relations are such that the tapered end of the shell is firmly clamped and frictionally held under impact and the reaction of the soil, the grip being the stronger the greater the force of driving.

Since numerous changes may be made in the form of execution of the invention it is desired that the foregoing description and drawings be understood in an illustrative rather than in a limiting sense.

I claim:

1. In apparatus for the construction of concrete piles in the ground, the combination of a sheet metal pile shell to constitute a permanent form to be sunk in contact with the soil, said shell having a penetrating point firmly connected with the lower end thereof, and a removable driving mandrel within said shell in driving contact with said point only, to pull the shell into the soil.

2. In apparatus for the construction of concrete piles in the ground, the combination of a substantially cylindrical sheet metal pile shell to constitute a permanent form to be sunk in contact with the soil, said shell having a penetrating point firmly connected with the lower end thereof, and a removable driving mandrel within said shell in driving contact with said point only, to pull the shell into the soil.

3. In apparatus for the construction of concrete piles in the ground, the combination of a sheet metal pile shell to constitute a permanent form to be sunk in contact with the soil, a closed penetrating end comprising a boot firmly connected with the shell, and a removable driving mandrel within said shell in driving contact with said penetrating end only, to pull the shell into the soil.

4. In apparatus for the construction of concrete piles in the ground, the combination of a sheet metal pile shell to constitute a permanent form to be sunk in contact with the soil, a closed penetrating end comprising a boot the top of which extends over the lower end of said shell and is welded thereto, and a removable driving mandrel within said

shell in driving contact with said penetrating end only, to pull the shell into the soil.

5. In apparatus for the construction of concrete piles in the ground, the combination of a corrugated sheet metal pile shell to constitute a permanent form to be sunk in contact with the soil, said shell having a penetrating point firmly connected with the lower end thereof, and a driving mandrel within said shell adapted to transmit the driving force to said point only without intimate contact with the surrounding shell, so that the shell extending upward from the point is pulled into the soil.
- 10
15. In the art of made-in-place concrete piles, the method which comprises utilizing a thin sheet metal shell as a form in which to cast the concrete form and providing this shell with an penetrating point, and sinking the shell into the soil by transmitting driving power through a mandrel in the interior of the shell to the point only so that the sheet metal form is pulled into the soil, after which the shell is filled with concrete.
